US00D543460S

(12) **United States Design Patent** (10) Patent No.: **US D543,460 S**
 Perry et al. (45) Date of Patent: **** May 29, 2007**

(54) **BOTTLE**

(75) Inventors: **Timothy Frederik Thomas Perry**,
 London (GB); **Edward Adamson**,
 London (GB)

(73) Assignee: **The Procter & Gamble Company**,
 Cincinnati, OH (US)

(**) Term: **14 Years**

(21) Appl. No.: **29/217,601**

(22) Filed: **Nov. 19, 2004**

(30) **Foreign Application Priority Data**

May 24, 2004 (EM) 000181573

(51) **LOC (8) Cl.** **09-01**

(52) **U.S. Cl.** **D9/516; D9/435; D9/452**

(58) **Field of Classification Search** D9/552,
 D9/516, 529, 574, 550, 435, 558, 562, 565,
 D9/549, 446, 452, 575; 215/220, 660, 675,
 215/669

See application file for complete search history.

(57) **CLAIM**

The ornamental design for a bottle, as shown and described.

DESCRIPTION

FIG. 1 is a perspective view of a bottle embodying my new design;

FIG. 2 is a front elevational view thereof;

FIG. 3 is a back elevational view thereof;

FIG. 4 is a side elevational view thereof;

FIG. 5 is a side elevational view thereof;

FIG. 6 is a top elevational view thereof; and,

FIG. 7 is a bottom plan view thereof.

The broken lines shown in the drawings are for illustrative purposes only and form no part of the claimed design.
